[57] CLAIM

The ornamental design for an infant swing cushion, as shown and described.

DESCRIPTION

FIG. 1 is a perspective view of the infant swing cushion.

FIG. 2 is an alternate perspective view of the infant swing cushion in full lines with an infant shown in broken lines representing environmental association matter being for illustrative purposes only and forming no part of the claimed invention.

FIG. 3 is a front elevational view of the infant swing cushion.

FIG. 4 is a rear elevational view thereof.

FIG. 5 is a right side elevational view thereof.

FIG. 6 is a left side elevational view thereof.

FIG. 7 is a top plan view of the infant swing cushion; and, FIG. 8 is a bottom plan view thereof.
